CLAIM

The ornamental design for a tri-spoke motor cap, as shown and described.

DESCRIPTION

FIG. 1 is a front perspective view of a tri-spoke motor cap according to the present invention;

FIG. 2 is a top view of the tri-spoke motor cap of FIG. 1; FIG. 3 is a side view of the tri-spoke motor cap of FIG. 1; FIG. 4 is a side view of the tri-spoke motor cap of FIG. 3 rotated about 180 degrees;

FIG. 5 is a side view of the tri-spoke motor cap FIG. 3 rotated about 90 degrees; and,

FIG. 6 is a bottom view of the tri-spoke motor cap of FIG. 1.

The broken line showing of environment is for illustrative purposes only and forms no part of the claimed design.

The tri-spoke motor cap is shown on an enlarged scale in FIGS. 2-6.
